UNITED STATES PATENT OFFICE.

FRANKLIN H. WOLEVER, OF CHICAGO, ILLINOIS, ASSIGNOR TO IDEAL ROLLER CO., OF CHICAGO, ILLINOIS, A CORPORATION OF DELAWARE.

CENTRIFUGAL CASTING-MACHINE.

1,317,120.

Specification of Letters Patent. Patented Sept. 23, 1919.

Original application filed April 21, 1917, Serial No. 163,579. Divided and this application filed July 9, 1917. Serial No. 179,420.

To all whom it may concern:

Be it known that I, FRANKLIN H. WOLEVER, a citizen of the United States, and a resident of Chicago, in the county of Cook and State of Illinois, have invented certain new and useful Improvements in Centrifugal Casting-Machines; and I do hereby declare that the following is a full, clear, and exact description thereof, reference being had to the accompanying drawings, and to the characters of reference marked thereon, which form a part of this specification.

This invention relates to a novel machine or apparatus for making compound rollers, for printing presses, type writing machines, clothes wringers and other uses, such for instance like the roller illustrated in my prior U. S. Letters Patent No. 1161756, dated November 25, 1915.

20 The present invention relates more particularly to an improved centrifugal casting machine for forming the shell or face layer of the roller, and to means for forming in the mold a liner against which the face layer is formed.

Among the objects of the invention is to produce a novel apparatus or machine for this purpose, so constructed and arranged as to facilitate the forming of the liner and the roller shell; to provide a machine of this character in which the centrifugal mold may readily be applied to and removed from the driving and supporting elements of the machine; to provide a novel means for centering the centrifugal mold in the supporting and driving elements; to provide novel means of cooling the mold during the shell forming or casting operation and to otherwise improve and simplify casting machines 40 of this general character.

The invention consists in the combination and arrangement of the parts shown in the drawings and described in the specification, and is pointed out in the appended claims.

45 In the drawings:—

Figure 1 is a side elevation of a casting machine embodying my invention, being part in section to show the mold liner.

Fig. 2 is an axial section of the mold 50 after the roller shell has been formed.

Fig. 3 is a similar view, showing the complete roller and adapter tube therein.

Fig. 4 is an enlarged axial section of the machine, broken away between its ends.

Fig. 5 is a section on the line 5—5 of Fig. 4.

The frame of the shell casting machine shown in Figs. 1 to 5, inclusive, comprises a bed 10 and head and tail stocks 11, 12, respectively. The tail stock is adjustable 60 longitudinally of the bed and is locked thereto by a screw 13 and nut 14, said bed being longitudinally slotted to receive a reduced portion of the tail stock.

The cylindric rotative shell mold 15 is 65 supported at its ends by conical centering members 16, 17, the mold being provided with end closing caps 18, which are annularly recessed to receive friction rings 19 that bear directly against the inner faces of 70 said conical centering and supporting members. The centering member 16 is apically apertured and is fixed to a rotative drive shaft 20, shown as hollow to provide for the escape of gases from the mold through the 75 apical aperture; and said shaft is mounted in suitable bearings 21 of the head stock. Power is transmitted to said shaft to rotate the mold by means of a pulley 22. A pipe 23 to provide for the escape of gas from the 80 mold, and provided with a valve 24, is connected by an elbow fitting 25 with said hollow drive shaft by a rotative joint, and is supported from the head stock by a 85 bracket 26.

The opposite conical centering and supporting member 17 is supported through a suitable antifriction bearing 27 on the tail stock so as to rotate freely with respect to the tail stock. It is provided with an apical 90 opening through which and the opening of the adjacent end cap extends a feed tube 28, which latter is removably seated in a horizontal bore in the tail stock and is provided with a shouldered outer end 29 that 95 limits the inward movement of the tube. Said tube is locked to the tail stock by a removable pin 30 and is closed at its outer end by a plug 31, which may be locked to the shouldered end of the tube by a pin 32. 100

Removal of the plug 31 affords access to the tube to clean the same. Upon removal of the pin 30 the said plug and tube, locked together by the pin 32, may be removed together for a more complete cleaning of the tube. The tube is apertured between its ends for communication with the outlet end 33 of a funnel 34 that is supported on the tail stock, and through which the liner and shell materials are poured into the mold.

In assembling the mold in the machine, the screw 13 is loosened and the tail stock adjusted on the bed to permit the mold to be passed between the enlarged end of the members 16 and 17, whereupon the tail stock, with its member 17 is slid inwardly to center the mold and clamp the mold between said conical centering and supporting members. Thereafter the screw 13 locks

the tail stock in place. After the mold has been assembled and is set in rotation, a quantity of the liner material, which has been accurately measured to produce a liner of a given internal diameter, is poured through the funnel 34 into the rotating mold, and centrifugal force developed by the rotation of the mold causes the liner material to form against the wall of the mold to produce a liner 35 of uniform thickness.

In order to prevent the liner material from cracking or checking, due to its contact with a cool mold wall, the mold is heated to a suitable temperature so as to allow the liner, when formed against the mold wall, to cool uniformly throughout its thickness and thereby avoid internal strains which may develop checks or cracks. A further advantage of preliminarily heating the mold is that the rise in temperature serves to slightly expand the mold whereby, upon cooling, the mold wall contracts upon the cooling liner and partly compensates for the shrinking of the liner due to its cooling. The liner is, moreover, elastic and is made of material that clings to the mold wall so that the contracting of the shell does not have the effect of parting the liner from the mold wall when the roller shell is formed therein.

After the liner is formed and hardened, the material to form the shell layer of the roller, which previously has been prepared by a partial vulcanizing process, is mixed with a further vulcanizing agent and is poured through the funnel into the rotating, lined mold; the charge of material having been accurately measured by a suitable measuring instrument to produce a shell of proper thickness and diameter to correspond with the overall diameter of the roller and other conditions. The mold continues to rotate at a suitably high speed, of five hundred or more revolutions per minute, until the shell material has been forced outwardly against the liner to form a shell 36

of uniform thickness and has hardened to maintain a permanent shape. The heat of vulcanization raises the temperature in the mold, and the resultant gases pass from the material to the interior of the shell and outwardly through the escape pipe 23. Likelihood of gases being pocketed in the shell is thereby avoided and the shell is formed with a very smooth outer surface of homogeneous texture and free from moisture. Air is circulated through the mold at high speed while the shell is being formed, as by means of a fan 37 connected to the pipe 23, so as to properly cool the shell material. Circulation of air through the mold while the liner is being formed and hardens is not required, and the valve 24 may be closed while the liner is being formed.

The liner material is of such character, or is so treated prior to the formation of the liner, as by the addition of a readily miscible agent having a higher melting temperature than the liner material, that its fusing temperature is relatively higher than the vulcanizing temperature of the shell material, but considerably lower than the fusing point of the shell after it has set. In this manner the forming surface of the liner is maintained intact against break-down under the action of the vulcanizing temperature of the shell while being formed which, should it occur to the slightest extent, would injure the face of the liner and consequently roughen the face of the shell and necessitate a grinding operation to properly finish the shell.

An advantage of the construction described lies in the ease with which the mold chamber 15 may be removed from the machine, it being only necessary to release the screw 13 and slide the tail stock outwardly such distance as will permit one end of the mold, which may be thus freed, to pass the larger end of its adjacent conical supporting member.

A further advantage found in the use of said construction is that the end caps 18 are held in place by the pressure which supports and centralizes the mold chamber in the machine, so that no special holding means are required to hold or retain the caps on the mold during the casting operation. Therefore, when the mold is removed said end caps may be readily detached from the ends of the mold preparatory to setting the mold in the stationery casting machine. The rubber rings or gaskets 19 provide efficient driving connections between the mold chamber and the supporting members.

The machine herein shown is adapted to be used with the form of casting machine shown in my co-pending application for U. S. Letters Patent, Serial No. 179421 filed of even date herewith, which said application and the present application are divisions of my

prior application for U. S. Letters Patent, Serial No. 163,579, filed on the 21st day of April, 1917.

I claim as my invention:—

- 5 1. Apparatus for casting roller shells comprising a mold, rotative centering members adapted to engage, center, and support molds of different diameters, and means to rotate one of said members.
- 10 2. Apparatus for casting roller shells comprising a mold, removable end caps for said mold, rotative centering members constructed to receive the ends of said caps to center and support the mold, and means to rotate one of said members.
- 15 3. Apparatus for casting roller shells comprising a frame, a mold, rotative supporting members adapted to engage the ends of the mold to center molds of varying diameters,
- 20 20 an anti-friction bearing between one of said members and the frame, and a drive shaft fixed to the other member.
- 25 4. A mold, rotative centering members to engage, center and support molds of different diameters, a rotative drive shaft fixed to one of said centering members, and a feed pipe extending through one of said members into said mold.
- 30 5. A mold, rotative centering members to center and support the mold, a rotative drive shaft fixed to one of said centering members, and a feed pipe extending through one of the members into said mold, said drive shaft being hollow to conduct air and gases from
- 35 35 said mold.
6. In combination with rotative, opposed, hollow, conical mold centering members and a mold supported on and centered by said members.
- 40 7. In combination with rotative, opposed, hollow conical, mold centering members, a mold supported on and centered by said members, and bearings for said centering members, with means for rotating one of
- 45 45 said members.
- 50 8. In combination with rotative, opposed hollow conical mold centering members and a mold supported and centered thereby, of a feed tube extending through one of the said members into the mold.
- 55 9. In combination with rotative, opposed hollow conical mold centering members and a mold supported and centered thereby, of a feed tube extending through one of the said members into the mold, and a removable axial plug to close said tube.
- 60 10. In combination with rotative, opposed hollow conical mold centering members and a mold supported and centered thereby, of a feed tube extending through one of the
- 65 65 said members into the mold, a bearing for said tube, means to detachably lock the tube in said bearing, a plug to close the tube, and other detachable means to lock said plug to said tube.
- 70 11. The combination with a frame, and a rotative, mold, of a feed tube extending at one end into the mold, with means to removably lock it to the frame to permit endwise withdrawal of the tube, and a plug to close the outer end of the tube, with other means to detachably lock it to said tube.
- 75 12. In combination with a frame, opposed, hollow conical mold supporting and centering members, a rotative drive shaft mounted in said frame and fixed to one of said members, an anti-friction bearing between the other member and said frame, said latter member being provided with an apical opening, a feed tube supported in the frame and extending at its inner end through said apical opening and into the mold, a hopper connected to the feed tube between the ends of the latter and a removably mounted plug to close the outer end of the feed tube.
- 80 85 13. A roller shell casting machine comprising a frame, a fixed head stock, a movable tail stock and mold supporting and centering members frictionally engaging the ends of the mold rotatively mounted on the head and tail stocks, respectively.
- 90 14. A roller shell casting machine comprising a frame, a fixed head stock, a movable tail stock, opposed mold centering and supporting devices to frictionally engage the ends of the mold, a rotative drive shaft mounted in the head stock and fixed to one of said members, a mold supported on and centered by said members, and means to feed material to said mold.
- 95 100 15. Apparatus for casting roller shells comprising a mold, rotative centering members to center and support the mold, removable end caps for said mold, adapted to engage said centering members and to be thereby held in place on the mold.
- 105 16. A mold, rotative centering and supporting members engaging the ends of the mold, a drive shaft fixed to one of the members, said shaft being hollow and communicating with the interior of the mold, and a suction fan connected to said hollow shaft.
- 110 115 In witness whereof I claim the foregoing as my invention, I hereunto append my signature in the presence of two witnesses at Chicago, Illinois, this 7th day of June, 1917.
